UNITED STATES PATENT OFFICE.

ELMER A. WATTS, OF SPRINGFIELD, OHIO, ASSIGNOR TO THE MILLER IMPROVED GAS ENGINE COMPANY, OF SPRINGFIELD, OHIO, A CORPORATION OF OHIO.

GAS COMPRESSOR.

Original application filed November 17, 1924, Serial No. 750,468. Divided and this application filed March 23, 1925. Serial No. 17,578.

My invention relates to gas compressors of the type shown and described in my application for patent filed November 17, 1924, Serial No. 750,468, of which this is a division.

It is my object to provide a compressor which may be either independently or directly connected to a source of power such as an internal combustion engine which will be adapted to compress air or other gases.

It is a further object of my invention to provide a positively operating compressor susceptible of maintaining high pressures of being easily started and of being constantly and uniformly cooled.

It is a further object to provide valves of simple construction which may be easily adjusted and repaired or replaced.

It is a further object of my invention to provide a rigid structure of great strength to withstand the pressures generated by the action of the compressor.

It is a further object to provide such a construction of valves and casings that the expansion which will take place due to heat may be compensated for without warping of the valves or the housings and without disrupting the structure to which the valves are attached.

It is a further object of my invention to provide internally cooled valve structures for use with the main circulation system for cooling the entire compressor.

It is a particular object of this invention to provide means for putting the engine into operation without the resistance of pressure which will be set up in the compressor and until the engine shall achieve the desired state of operation and speed when the compressor can be thrown into operation and pressure built up.

Referring to the drawings:

Figure 1 is a section through the compressor, showing a portion of the valves in section and a portion of the valves in elevation and the piston and piston rod in elevation;

Figure 2 is an enlarged section through the left hand exhaust valve and inlet valve;

Figure 3 is an enlarged section through the right hand end of the unit;

Figure 4 is a plan view of one of the inlet valves taken on the line 4-4 of Figure 1;

Figure 5 is a similar view taken on the line 5-5 of Figure 1; and

Figure 6 is a view showing the complete unit of compressor and engine to which it is directly connected in one unitary structure.

Figure 7 is a plan view partly broken away of the engine showing the means for its connection to the compressor, not shown.

Referring to the drawings in detail, 1 is a standard or support for supporting the compressor structure. 2 is a casing forming a part of the engine structure to which the compressor proper is connected by an intermediate chamber formed by the cylindrical casing 3. This casing serves to support a guide through suitable bearings for the compressor piston rod 4. A wall 5 is embraced between the structure 2 and the cylindrical casing 3 and is held in place by these two structures which are bolted together by the bolts 6. The piston rod 4 operates through an aperture in the center of the member 5. 70 Packing 7 and a threaded sleeve 8 serve to seal the chamber 3 from the main portion of the engine 2.

The other end of the casing 3 rests on shoulders 9 formed on the end of the outside casing 10 of the compressor cylinder. An opening 11 is formed in the top of the casing 10 closed by the cover 12 so that it is possible to gain access to the chamber 3 for adjusting the packing about the piston rod 4. Packing is provided around the piston rod 4 where it enters the compressor cylinder. This packing consists of soft packing rings 13 within a sleeve 14. This sleeve carries a threaded sleeve engaging with the piston rod designated 4 which compresses the soft packing 13 against the internal shoulder 15 carried on the sleeve 14. The sleeve 14 has a shoulder 16 abutting against the end of the outside casing 10 of the compressor cylinder head. Oil is delivered to an oil passageway 17 through the sleeve 14 and to the metallic packing members 18 which are contained with a cup shaped structure 19 formed integral with the cylinder 100 structure of the compressor and projecting into the cylinder 20 thereof.

It is apparent that it is possible to remove these two packing members, the soft packing and the metallic without disturbing each other as they are contained in separate units.

It will be noted that the metallic packing consists of a series of successive cups 19 containing the packing members 18. The oil passageway 17 passes through these cups 110

for supplying lubricant at this important point.

Turning to the compressor proper, it will be noted that there is an end wall 21 forming the outside end of the compressor and an interior end wall 22 spaced therefrom to provide a circulation passageway 23 for carrying fluids. There is a cylindrical outside casing 24 forming the exterior wall of the compressor. An interior wall is provided at 25. Between these walls on the upper half of the compressor are the passageways 26 communicating with the intake port 27 forming the intake passageways leading to the intake valves at either end of the passageways at either end of the compressor.

At the bottom of the compressor the discharge passageway which is marked 28 leads to a discharge port 29.

Referring to the intake valve, a plate 30 is bolted to the top of the casing 10 by the bolts 31. This plate carries an adjusting screw 32 threaded into the plate and having a lock nut 33. The lower end of this screw bears upon the head 34 of a spider having arms 35 which project downwardly until they are joined to a ring 36 which rests within the interior wall of the compressor casing 22. This ring is shouldered at 37 to fit upon an outer edge of a valve seated plate 38 having a plurality of spaced openings 39. The periphery of this seated plate is cut away to receive the projecting edge of the ring 37 which projects into the openings between the edge of the plate 38 and the wall 22.

The openings 39 which are the intake openings in the valve seat 38 are closed by the valve members 41 which are provided with downwardly extending hollow cylindrical sleeves 42 which act as the valve stem for the valves 41. These stems are guided in apertures 43 formed in a ring 44 which is seated on shoulders 45 formed in the wall of the compressor. It will be understood that the fit between this ring 44 and the walls of the compressor are gas tight fits. Helical springs 46 are provided within the valve stems and seated within the apertures 43 to maintain the valves 41 against the seat. This ring 44 has a central passageway 47 for the passage of air into the cylinder 20. A piston 48 works in this cylinder on the piston rod 4.

Directly beneath each of the intake valves which are exactly alike and located at either end of the cylinder is the discharge valve. This valve consists of a seat plate 49 having a plurality of ports 50 closed by valves 51 which have hollow valve stems 52 containing valve springs 53. The stems are guided in upwardly projecting sleeves 54 which form the seats for the valve springs 53 as well as guides for the valve stem. These

sleeves 54 are mounted on a tubular casing 55 which has an internal rib 56 spaced therefrom. A water passageway 57 is provided on the interior of this casing 55 to cool the valve structure as far as possible. The circulation passage 57 is connected with the rest of the circulation system for cooling the cylinder and the cylinder head of the compressor. Centrally located in this casing 55 is a tubular chamber 58 containing a spacing member 59, one end of which is seated in the valve seat 49 through a centering pin 60. This passageway has in its opposite end a downwardly extending rod 61 which projects through the cylindrical passageway 58 into a centering passageway 62 formed in the end of the casing 55. A helical spring 63 is interposed between the end of the piston 59 and the bottom of the cylindrical passageway 58. The casing 55 is notched on either side as at 64 to receive a cross pin 65 carried by the shoulder or piston 59.

The bottom of the casing 55 is formed into a pair of spaced walls 66 and 67. These walls are spaced to form water circulation passageways 68. The top of the casing 55 which forms the wall of the cylinder 58 is connected to the wall 66 of the rib 56, thus tying the structure together and re-enforcing it at the point of greatest strain. A clean out plug 69 is provided in the wall 66. The inner wall 67 is provided with inwardly extending shoulders for receiving the edge of the cylinder casing proper. This serves to center this detachable valve supporting casing 55 and its walls 67 and 66. This unit is bolted by the bolts 71 to the compressor and is detachable therefrom as a unit. The valve seat itself has a shoulder 72 for seating it upon the compressor casing or wall.

The reason for providing the spring shoulder 59 is to accommodate for the variation in distance between the shoulder 72 and the shoulder 70.

It will be noted that the passageway along the cylinder head as at 23 for the cooling fluid is very much larger than the passageway 73 the difference being that the passageway 23 is about one-half inch by two inches while the passageway 73 is a round hole about a half inch in diameter. This is due to the fact that it is desirable to secure greater cooling of the cylinder head than in the neighborhood of the passageway 73. The air passes from the cylinder 20 through the ports 50 into the area 74 around the wall 75 of the water passageway 73 into the discharge passageway 28 to the discharge passageway 29.

One of the features of advantage of this compressor is that it has the detachable cylinder liner so that bores of the cylinder can be formed by substituting liners with-

out disturbing the remainder of the engine save the detachable piston 48 which is held on the piston rod by the nut 76.

This liner is designated 77. It is formed with shoulders 78 for feeding against the compressor casing. It also has rings at either end designated 79 to form the end walls for the main cooling fluid passageways 80 around the cylinder liner 77 and between the liner and the walls 25 which form the inside walls for the intake and discharge passageways. These passageways for the cooling fluid 80 communicate with the passageway 73 for circulating the fluid around the discharge valves to the cylinder head.

The forward end of the cylinder has a circulation passageway for fluid marked 81. The cylinder head is designated 82 with an outside wall 83 which forms an inside wall of a by-pass passageway 84, the outside wall of which is marked 85. This wall 85 is the outside wall of the compressor structure. The passageway 84 forms a by-pass passageway leading directly over to the intake passageway 26 through a valve opening 86 closed by a valve 87 to the forward discharge passageway 88 beneath the forward discharge valve. The reason for this passageway is to permit of the by-pass passageway passing directly over the intake to the discharge during starting to relieve the engine of the compressing operation until it gets started. When the valve 87 is open this permits the gas to circulate in the cylinder which is to be compressed without building up the pressure. The valve 87 is controlled by a valve stem 89 operated by a hand wheel 90. This valve stem is carried in a supporting plate 91 of any desired construction. If desired this by-pass 84 may be connected direct to the discharge 29, but for the purpose of convenience it is arranged as shown in the drawings.

It will be seen from the arrangement of the several parts that I have provided a main casing having spaced walls to form intake and discharge passageways. I have also provided a detachable liner and valve assemblies which are completely detachable and may be removed as a unit with the least disturbance to the rest of the mechanism. I have provided a by-pass passageway integral with the compressor for circulation of the gas directly without going through the compressor cylinder to facilitate starting. I have provided water cooled exhaust valves and a water cooled cylinder and cylinder head. I have also provided directly opposed intake and discharge valve assemblies in pairs at either end of the cylinder.

It is possible with my compressor to secure a structure which will automatically compensate for the changes in temperature,

which will stand high pressure and which may be modified to take varying bores so that the structure will be adaptable to a number of different conditions without having to have a complete reconstruction of the compressor, so that as in gas fields it is possible to vary this unit to meet varying conditions.

It will be understood that I do not desire to confine my invention to the specific details but comprehend with my claims such modifications as may be necessary to adapt the invention to varying conditions.

I have shown the compressor directly connected to an internal combustion engine as that is my preferred construction, but I do not desire to confine myself to this source of motive power only. I have designated the internal combustion engine generally as a source of motive power 91.

The piston rod 4 is connected to the slide block 92 which carries the cross head 93 and a link 94. The compressor link is mounted on the crank 95 on which is the common crank for the internal combustion link 96. This crank is mounted on the crank shaft 97 which has a common crank shaft for the two units.

It will be thus seen that the compressor is mounted on the single bed 98 which supports the internal combustion engine structure, the common fly wheel 97^a and crank structure and the compressor with the engine. It will also be noted that the main casing or frame of the engine 99 acts as the guide for the slide-block 92 so that there is perfect alignment between the internal combustion unit and the piston of the compressor unit, giving great rigidity to the entire structure.

Having thus fully described my invention, what I claim as new and desire to secure by Letters Patent is:—

1. In a compressor characterized by having a compression cylinder, inlet and exit passageway and valves therefor, an integral valved head having a communicating passageway from the inlet valve to the outlet valves contained within the integral casing whereby the contents of the compressor may circulate through the valves, the integral passageway, and the cylinder, without building up pressure when said passageway is opened, and a manually operated valve member for controlling said passageway, said manually operated valve being unconnected with said inlet and outlet valves and located between the same in the cylinder head.

2. In a compressor characterized by having a compression cylinder, inlet and exit passageway and valves therefor, an integral valved head having a communicating passageway from the inlet valves to the outlet valves contained within the integral casing whereby the contents of the compressor may

circulate through the valves, the integral passageway, the cylinder, without building up pressure when said passageway is opened, and a manually operated valve member for controlling said passageway, said manually operated valve being unconnected with said inlet and outlet valves and located between the same in the cylinder head, the walls of said passageway being so

arranged that the inner wall is formed from the water jacket wall of the cylinder and the outer wall is an integral wall constituting the exterior of the cylinder head a portion of which defines the inlet and outlet passageway.

15

In testimony whereof, I affix my signature.

ELMER A. WATTS.
